DESIGN FOR A COMBINATION LAMP AND MIRROR

Daniel E. Reed, Norwalk, Conn., assignor to Yankee Metal Products Corp., Norwalk, Conn., a corporation of New York

Application September 23, 1940, Serial No. 95,292

Term of patent 14 years

To all whom it may concern:

Be it known that I, Daniel E. Reed, a citizen of the United States, residing at Norwalk, in the county of Fairfield and State of Connecticut, have invented a new, original, and ornamental Design for a Combination Lamp and Mirror, of which the following is a specification, reference being had to the accompanying drawing, forming a part thereof, and in which:

bination lamp and mirror, showing my new design.

Fig. 2 is a rear view.

Fig. 3 is a front view.

The dominant features of my design are shown in solid lines.

I claim:

The ornamental design for a combination lamp and mirror, as shown and described.

DANIEL E. REED.
